US0D1112095S

(12) **United States Design Patent** (10) **Patent No.:** **US D1,112,095 S**
(45) **Date of Patent:** **** Feb. 10, 2026**

(54) **CONNECTOR PLUG**

(71) Applicant: **Dongguan Chogori Electric Technology Co., Ltd**, Dongguan (CN)

(72) Inventor: **Yuanze Wu**, Dongguan (CN)

(73) Assignee: **DONGGUAN CHOGORI ELECTRIC TECHNOLOGY CO., LTD**, Guangdong (CN)

(**) Term: **15 Years**

(21) Appl. No.: **29/903,392**

(22) Filed: **Sep. 22, 2023**

(30) **Foreign Application Priority Data**

Mar. 24, 2023 (CN) 202330148859.7

(51) **LOC (15) Cl.** **13-03**

(57) **CLAIM**

The ornamental design for a connector plug, as shown and described.

DESCRIPTION

FIG. 1 is a front view of a connector plug showing my new design.

FIG. 2 is a rear view thereof.

FIG. 3 is a left side view thereof.

FIG. 4 is a right side view thereof.

FIG. 5 is a top side view thereof.

FIG. 6 is a bottom side view thereof.

FIG. 7 is a front perspective view thereof; and,

FIG. 8 is a rear perspective view thereof.

The broken lines included in FIG. 1 define the boundaries of the claimed design and form no part of the claimed design. All features contained between the broken lines illustrate portions of the connector plug that form no part of the claimed design.

1 Claim, 8 Drawing Sheets
